HAMMER OR THE LIKE

Jerome Vogel, 48 Stewart Ave.,
Pittsburgh, Pa. 15227

Filed Sept. 12, 1966, Ser. No. 3,827

Term of patent 14 years

(Cl. D93—4)

The figure is a perspective view of the hammer or the like showing my new design.

The side opposite the side shown is substantially identical to the side shown.

I claim:

The ornamental design for a hammer or the like, as shown and described.
